UNITED STATES PATENT OFFICE.

JULIUS FOWL, OF NEW YORK, N. Y.

WHEEL FOR TRUCKS, BASKETS, &c.

SPECIFICATION forming part of Letters Patent No. 674,577, dated May 21, 1901.

Application filed November 3, 1900. Serial No. 35,398. (No model.)

To all whom it may concern:

Be it known that I, JULIUS FOWL, a citizen of the United States, residing at New York, in the county of New York and State of New York, have invented certain new and useful Improvements in Wheels for Trucks, Baskets, &c.; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to wheels for trucks and baskets, &c., and has for one object to produce a noiseless wheel of this character that will not become loose in its parts through use; and a further object is to produce a wheel 20 of this character that can be readily assembled without the use of tools, and with these and minor objects my invention consists in parts and combinations of parts, as will be hereinafter more fully set out.

25 In the drawings, Figure 1 is a central vertical section of a wheel constructed according to my invention. Fig. 2 is a detail view of two parts of the wheel in elevation. Figs. 3 and 4 are side elevations of the respective 30 parts shown in Fig. 2. Fig. 5 is a side elevation of my improved wheel.

1 represents one member of the wheel, having an enlarged central portion 2, through which is formed an opening or bearing to 35 form a box for the axle upon which the wheel is adapted to be mounted.

3 is an oil-duct formed in the enlarged portion 2, leading into the axle-box.

4 is an annular flange extending at right 40 angles from and integral with the member 1, the inner face of which is provided with suitable screw-threads.

5 is an annular outwardly-extending flange integral with the member 1, the flange being 45 undercut, as at 6.

7 is the other member of the wheel, having an enlarged portion 8 similar to the enlarged portion 2 of the member 1 and an outwardly-extending integral annular flange 9 undercut, as at 10, which, with the undercut 6 on 50 the other member of the wheel when the parts

are assembled, forms a wedge-shaped annular groove around the wheel.

11 is an inwardly-extending annular flange, from which extends a similar flange 12, provided on its outer face with suitable screw-threads adapted to intermesh with the screw-threads on the flange 4 of the member 1.

Each of the members 1 and 2 is provided with the opening 12, adapted to register with each other when said members are assembled, and 14 is a locking-key adapted to pass through both of the openings 13, thereby locking the members 1 and 7 securely together against rotation upon each other. 15 is a rubber or 65 other noiseless tire, which is placed between two members of the wheel before said members are entirely secured together.

It will be noticed in Fig. 1 that the enlarged portions 2 and 8 abut when the members are assembled.

To assemble the wheel, the rubber tire is first placed upon one or the other of the members, preferably on the member 2, whereupon the member 7 is screwed to the member 2, 75 and revolved so that the screw-threads on the respective flanges 4 and 12 draw the members firmly together, thus rigidly clamping the rubber tire 15 between the undercut annular flanges 5 and 9, as shown in Fig. 5, 80 whereby the said tire is prevented from creeping. As soon as the parts are thus assembled the locking-key 14 is slipped through the openings 12 in the respective members, thus securing the members against rotation upon 85 each other.

The construction of this wheel is so simple that any one can assemble it without tools, and a further advantage of its simplicity is that the parts are interchangeable and the 90 tire is, by reason of the annular inwardly-projecting flanges 4 and 11, given a firm tread or base.

What I claim, and desire to secure by Letters Patent, is—

1. A wheel of the character described, comprising one member having an inwardly-extending annular flange provided with screw-threads on its inner face, and an annular peripheral flange and a second member having 100 an inwardly-extending annular flange, from which extends a second annular flange, screw-

threaded on its outer face, a peripheral annular flange, and a rubber or other noiseless tire screwed between said peripheral annular flanges.

- 5 2. A wheel of the character described, comprising one member having an inwardly-extending annular flange, provided with screw-threads on its inner face, a peripheral undercut flange and a central enlarged portion 10 in which is formed an axle box or bearing and a second member comprising an inwardly-extending flange, an inwardly-extending annular flange integral with the flange just named, an enlarged central portion in which

is formed an axle box or bearing and an annular undercut flange, a rubber or other noiseless tire secured between said undercut flanges, openings in both of said members adapted to register when the parts are assembled and a locking-key adapted to pass 20 through both of said openings.

In testimony whereof I affix my signature in presence of two witnesses.

JULIUS FOWL.
